SANITARY SMOKING STEM FOR PIPES,
CIGARS, AND THE LIKE

Joseph Szilagyi, New York, N. Y.

Application February 1, 1932. Serial No. 590,156

5 Claims. (Cl. 131—12)

This invention relates to new and useful improvements in a sanitary smoker's stem for pipes, cigars and the like.

The invention has for an object the construction of a stem which is characterized by a hollow divided into two compartments with a plug having peripheral grooves to allow passage of smoke from one to the other, and the provision of tubes connecting one of the compartments with the 10 mouthpiece of the stem and the other with the head of the stem.

The invention has for a still further object the novel arrangement whereby the mouthpiece is detachably held in place.

15 Furthermore, this invention proposes the provision of means allowing the withdrawal of the plug which divides the hollow chamber into the compartments mentioned.

Furthermore, it is another object of this invention to provide means for varying the passage formed by the peripheral grooves upon the plug so that the pipe may be set at the most advantageous condition for smoking.

As another object it is proposed to construct an 20 article of the class described which is of simple durable construction, dependable in use and efficient in operation and which can be manufactured and sold at a reasonable cost.

For further comprehension of the invention, 25 and of the objects and advantages thereof, reference will be had to the following description and accompanying drawing, and to the appended claims in which the various novel features of the invention are more particularly set forth.

30 In the accompanying drawing forming a material part of this disclosure:—

Fig. 1 is a sectional view of a pipe constructed according to this invention.

Fig. 2 is a transverse sectional view taken on 40 the line 2—2 of Fig. 1.

Fig. 3 is a longitudinal sectional view of a cigar holder constructed according to this invention.

Fig. 4 is a fragmentary view of a modified form of plug for use in the sanitary stem.

45 Fig. 5 is an elevational view looking in the direction of the line 5—5 of Fig. 4.

The smokers' sanitary stem for pipes, cigars and the like is indicated by reference numeral 10 and is shown formed with a head end 11 which 50 connects with the bowl 12 of a pipe as shown in Fig. 1 or with a portion 12' adapted to receive the end of the cigar or the like. The main portion of the stem 10 is formed with a hollow 13 communicating with the tail end. A removable mouthpiece 14 closes the hollow 13. A plug 15 is located

within the hollow 13 and divides it into two compartments indicated by reference numerals 16 and 17 respectively.

A smoke tube 18 extends through the head end 11 of the stem and through the plug 15 so that 60 smoke from the bowl or cigar may be discharged into the compartment 17. A second tube 19 extends from the compartment 16 through the plug 15 and connects with the mouthpiece 14.

The tube 18 is threaded at one end 20 and 65 threadedly engages within a bushing 21 formed with external threads engaging within the head end 11. The tube 18 is axially arranged with the plug 15 so that the plug may be turned to engage or disengage the tube from the bushing. 70 The outer end of the plug 15 is formed with openings 22 for receiving a turning tool which may be engaged in from the open end of the stem to accomplish proper connection of the tube 18 with the bushing. The outer end of the tube 75 19 is formed with threads 23 which threadedly engage into the inner end of the mouthpiece 14. A set screw 24 mounted upon the mouthpiece 14 locks the mouthpiece against the portion 23.

When the smoker draws through the mouthpiece 14 the smoke from the cigar or the bowl 12 passes through the tube 18 into the chamber 17, then through the peripheral grooves of the plug 15 to the compartment 16 and thence through the tube 19 and the mouthpiece 14. 80 85 A tortuous path of the smoke causes the vapors contained therein to be deposited within the stem and thus a dry smoke is produced. The parts may be cleaned by loosening the set screw 24, then removing the mouthpiece 14 and finally 90 removing the plug 15 which carries with it the tubes 18 and 19.

In the modified form of the device illustrated in Figs. 4 and 5 a plug for dividing the chamber of the stem into the two compartments has 95 been shown which is arranged so as to be formed with peripheral passages which are adjustable to control the passage of the smoke. More particularly, the plug is formed from an outer end disc 25 which is fixed upon the tubes 18 and 100 19. The outer end disc 25 is formed with a recess 26 adapted to be engaged by a flange 27 from a ring member 28 adjacent to the disc 25. A plurality of other ring members 28 are interengaged with each other and altogether compose 105 the plug which is indicated generally by reference numeral 15'. The inner disc which concludes the plug 15' is indicated by reference numeral 29 and resilient means in the form of springs 30 act between the ring 29 and the 110

disc 25 to frictionally hold all of the discs 28 tightly against each other. The construction allows the rings 28 to be slightly turned so that the grooves are out of line from each other any 5 desirable amount which control the passage of the smoke between the compartments.

While I have shown and described the preferred embodiment of my invention, it is to be understood that I do not limit myself to the 10 precise construction herein disclosed and the right is reserved to all changes and modifications coming within the scope of the invention as defined in the appended claims.

Having thus described my invention, what I 15 claim as new, and desire to secure by United States Letters Patent is:—

1. A stem for pipes, cigar holders and the like, said stem having a head end and a hollow forming a chamber, in combination with a removable 20 mouthpiece closing said chamber, a plug dividing said chamber into two compartments and formed with peripheral grooves allowing communication between the compartments, a smoke tube extended through the head end and through said plug 25 into one of said compartments, a second smoke tube extended from the mouthpiece through the plug into the other compartment, and means for varying the peripheral passage of the grooves on said plug.

30 2. A stem for pipes, cigar holders and the like, said stem having a head end and a hollow forming a chamber, in combination with a removable mouthpiece closing said chamber, a plug dividing said chamber into two compartments and formed with peripheral grooves allowing communication between the compartments, a smoke tube extended through the head end and through 35 said plug into one of said compartments, a second smoke tube extended from the mouthpiece 40 through the plug into the other compartment, and means for varying the peripheral passage of the grooves on said plug, comprising a plurality of adjacent rings forming the plug, and means for adjustably holding said rings in relation to 45 each other.

3. A stem for pipes, cigar holders and the like, said stem having a head end and a hollow forming a chamber, in combination with a removable mouthpiece closing said chamber, a plug dividing 50 said chamber into two compartments and formed

with peripheral grooves allowing communication between the compartments, a smoke tube extended through the head end and through said plug into one of said compartments, a second smoke tube extended from the mouthpiece through the plug into the other compartment, and means for varying the peripheral passage of the grooves on said plug, comprising a plurality of adjacent rings forming the plug, and means for adjustably holding said rings in relation to each other, comprising recesses formed in the rings and engaged by flanges formed on adjacent rings. 80

4. A stem for pipes, cigar holders and the like, said stem having a head end and a hollow forming a chamber, in combination with a removable mouthpiece closing said chamber, a plug dividing said chamber into two compartments and formed with peripheral grooves allowing communication between the compartments, a smoke tube extended through the head end and through said plug into one of said compartments, a second smoke tube extended from the mouthpiece through the plug into the other compartment, and means for varying the peripheral passage of the grooves on said plug, comprising a plurality of adjacent rings forming the plug, means for relatively adjusting the said rings, and means for holding the rings in the adjusted positions. 90

5. A stem for pipes, cigar holders and the like, said stem having a head end and a hollow forming a chamber, in combination with a removable mouthpiece closing said chamber, a plug dividing said chamber into two compartments and formed with peripheral grooves allowing communication between the compartments, a smoke tube extended through the head end and through said plug into one of said compartments, a second smoke tube extended from the mouthpiece through the plug into the other compartment, and means for varying the peripheral passage of the grooves on said plug, comprising a plurality of adjacent rings forming the plug, means for relatively adjusting the said rings, and means for holding the rings in the adjusted positions, comprising resilient means acting between the end rings to frictionally hold all of the rings tightly against each other. 100
